US00D842333S

(12) **United States Design Patent** (10) Patent No.: **US D842,333 S**
Connor et al. (45) Date of Patent: ** Mar. 5, 2019

(54) **DISPLAY SCREEN OR PORTION THEREOF
WITH GRAPHICAL USER INTERFACE**

(71) Applicant: **Apple Inc.**, Cupertino, CA (US)

(72) Inventors: **Teofila Connor**, San Francisco, CA (US); **Allison W. Dryer**, San Francisco, CA (US); **Cas G. Lemmens**, San Francisco, CA (US); **Marcel van Os**, San Francisco, CA (US)

(73) Assignee: **Apple Inc.**, Cupertino, CA (US)

(**) Term: **15 Years**

(21) Appl. No.: **29/606,386**

(22) Filed: **Jun. 4, 2017**

(51) LOC (11) Cl. **14-04**

(52) U.S. Cl.

USPC **D14/489**

(57) **CLAIM**

The ornamental design for a display screen or portion thereof with graphical user interface, as shown and described.

DESCRIPTION

FIG. 1 is a front view of a display screen or portion thereof with graphical user interface showing the claimed design; and,

FIG. 2 is another embodiment thereof.

The outermost broken lines in the figures show a display screen or portion thereof, and form no part of the claimed design. The other broken lines in the figures show portions of the graphical user interface that form no part of the claimed design.

1 Claim, 2 Drawing Sheets
